UNITED STATES PATENT OFFICE.

CHARLES A. KARPENSTEIN, OF CHICAGO, ILLINOIS.

WINDOW CONSTRUCTION.

Application filed April 13, 1922. Serial No. 552,260.

To all whom it may concern:

Be it known that I, CHARLES A. KARPENSTEIN, a citizen of the United States, and a resident of Chicago, in the county of Cook and State of Illinois, have invented a new and useful Improvement in Window Constructions, of which the following is a full, clear, and exact description.

My invention relates to improvements in window constructions, and it consists in the combinations, constructions, and arrangements herein described and claimed.

An object of my invention is to provide a window construction in which the movable sash is prevented from any lateral play, thereby obviating the rattle which is customary from the ordinary window.

A further object of my invention is to provide a device of the character described in which the movable sash is pivotally mounted, whereby the sash may be readily swung into any desired position.

A further object of my invention is to provide a device of the character described in which the sash is frictionally held in adjusted position.

A further object of my invention is to provide a device of the character described which provides an air-tight connection between the window frame guide-ways and the sash.

Other objects and advantages will appear in the following specification, and the novel features of the invention will be particularly pointed out in the appended claim.

My invention is illustrated in the accompanying drawings, forming part of this application, in which—

Figure 1 is a front elevation of the device, portions thereof being shown in section,

Figure 2 is a section along the line 2—2 of Figure 1,

Figure 3 is a perspective view of a portion of the device, and

Figure 4 is a section along the line 4—4 of Figure 1.

In carrying out my invention, I make use of the ordinary window frame 1 which has a weight receiving compartment 2 therein. A window sash 3 is mounted in the window frame 1 and is provided with V-shaped groove sides 4, these sides being lined with a metal plate 5. A guide member 6 is slidably disposed in a groove 7 in the frame 1 and has a V-shaped portion 8 which

is snugly received within the groove 4. The guide 6 is connected to the plate 5 by means of a pivot pin 9 (see Figure 1). From this construction it will be apparent that the sash 3 may be swung about the pivot 9 and will move the guide 6 inwardly to the dotted line position shown in Figure 4.

The guide 6 is connected by means of links 10 with a friction plate or shoe 11. This shoe is adapted to engage with the inner wall of the groove 7 and thereby holds the sash 3 against movement. The ordinary window weight 12 is connected by means of a chain 13 to the upper link 10 (see Figure 3). The chain 13 is passed over an idler pulley 14 which is carried by the frame 1. It is obvious that the weight 12 tends to swing the links 10 upwardly about their pivots 15 so as to throw the shoe 11 into engagement with the frame 1. The other side of the window sash 3 is provided with the guide member 6 and the shoe 11 in the same manner as heretofore described.

From the foregoing description of the various parts of the device, the operation thereof may be readily understood. It is obvious that the window sash 3 may be raised or lowered in the ordinary manner, and it will be supported in adjusted position by means of the weight 12. The weight 12, however, is not connected to the window sash 3 in the ordinary manner, but as heretofore stated, is connected to the upper link 10, whereby the weight of the member 12 will cause the shoe 11 to engage with the frame 1 and prevent the window sash 3 from lateral movement as well as upward movement. The weight 12 furthermore acts as a yielding means which permits the guide member 6 to move inwardly toward the shoe 11. As heretofore stated, the guide member 6 is moved laterally when the window sash 3 is swung about the pivots 9. The sash 3 carries a sleeve 9' that slidably receives the pin 9. In Figure 4, I have shown the window sash 3 swung into the dotted line position, and have shown the member 6 moved inwardly so that the vertex of the member 6 is disposed substantially flush with the inner side of the frame 1. The window sash 3 can be lowered in the ordinary manner, and will cause the shoe 11 to move downwardly therewith. By pivoting the window sash 3 to the guide member 6, I provide a novel means by which the inner and outer sides of the window may be

readily washed, without the necessity of a person standing on the outside of the window. The upper sash 16 may be provided with a guide member 6 and shoe 11 in the same manner as is the lower sash 3. I claim

The device may be readily secured to a window of ordinary construction with but slight alterations in the latter. The device provides a novel means by which any lateral movement of the window is obviated, and which, at the same time, permits the window to be swung with respect to the frame 1. I prefer to have the guide members 6 engage with a plate 5 instead of with the window sash 3 so as to reduce the friction and wear between the moving parts to a minimum. The weight 12 also aids in bringing the sash 3 back into a vertical position, since it tends to move the guide member 6 toward the sash 3. The device is simple in construction, and is durable and efficient for the purpose intended.

In a window construction, a sash having a groove in its side, a metal plate lining said groove, a sash guide member pivotally secured to said plate and having a projection receivable in said groove, the means pivotally securing said plate and guide member together comprising a sleeve extending from said plate and into said sash, and a pin carried by said guide member and slidably and rotatably received in said sleeve, a friction shoe, links connecting said shoe with said guide, said links extending at an angle with respect to said shoe and guide, a chain having one end secured to one of said links, between the moving parts to a minimum. The weight connected to said chain so as to cause said chain to swing said link and force the shoe into engagement with the wall of the groove in said window frame.

CHARLES A. KARPENSTEIN.
